UNITED STATES PATENT OFFICE.

EPHRAIM LIGGINS, OF WALSALL, ENGLAND.

DESIGN FOR A TROUGH FOR HARNESS-SADDLES.

SPECIFICATION forming part of Design No. 31,097, dated June 27, 1899.

Application filed May 15, 1899. Serial No. 716,965. Term of patent 14 years.

To all whom it may concern:

Be it known that I, EPHRAIM LIGGINS, a subject of the Queen of Great Britain, residing at Walsall, in the county of Stafford, England, have invented and produced a new and original Design for a Trough for Harness-Saddles, of which the following is a full, clear, and exact description.

The invention relates to a new design for the troughs of saddles for harness.

I will describe my invention by the aid of the accompanying drawings, in which—

Figure 1 is a central longitudinal section of my saddle-trough. Fig. 2 is a central cross-section of Fig. 1. Fig. 3 is a perspective view.

In all the figures like parts are indicated by similar letters of reference.

In carrying my invention into effect I construct the trough a with a bottom a' of the required shape to fit the flaps of the saddle and

having spread-out ends and the usual vertical sides a^2 , running the entire length of the trough. The upper edges a^3 of the said vertical sides are bent inward. I arrange a roller a^4 on a pin a^5 at each end of the edges a^3 and 25 extending across from side to side of the trough. Countersunk holes a^6 , a^7 , and a^8 are arranged as shown.

b are the rein-rings, and b' clips therefor.

Having described my invention, what I 30 claim as new, and desire to secure by Letters Patent, is—

The design for a trough for harness-saddles, substantially as shown and described.

In testimony whereof I affix my signature 35 in presence of two witnesses.

E. LIGGINS.
